Primary Examiner — Karen S Acker(74) Attorney, Agent, or Firm — Roddy M. Bullock(57) CLAIM

The ornamental design for a paper towel, as shown and described.

DESCRIPTION

The sole FIGURE is a top plan view of a paper towel showing our new ornamental design.

The claim is directed to the horizontal lines on the top and the bottom of the paper towel and the shapes bounded by solid line. The broken lines in the FIGURE form no part of the claimed design. The paper towel is flat and planar.
